UNITED STATES PATENT OFFICE.

ALEXANDER T. BROWN, OF SYRACUSE, NEW YORK.

CLEANING ATTACHMENT FOR TYPE-WRITING MACHINES.

SPECIFICATION forming part of Letters Patent No. 427,393, dated May 6, 1890.

Application filed October 28, 1889. Serial No. 328,409. (No model.)

To all whom it may concern:

Be it known that I, ALEXANDER T. BROWN, residing at Syracuse, in the county of Onondaga and State of New York, have invented 5 certain new and useful Improvements in Cleaning Attachments for Type-Writing Machines, of which the following is a specification, reference being had therein to the accompanying drawings.

10 This invention relates to cleaning attachments or brushes for type-writing machines.

The object of the invention is to produce a cleaner or brush attachment for type-writing machines in which the brush may be reciprocated across the face of the type in such manner as to clean all or a large number of the letters simultaneously.

Figure 1 is a vertical longitudinal section of so much of a common form of type-writer 20 as is necessary to illustrate the invention with brush and brush-moving devices attached. Fig. 2 is a plan of so much of the basket and brush as will show the general relation of parts.

25 A indicates the base, B the posts or supports, and C the ring or basket, of a well-known machine like the "Standard."

30 D denote the type-bars, E the connecting-wires, and F the key-levers. Only a few 30 of the type-bars are shown.

G indicates a cross-bar or bracket below the type-levers, having a hub bearing or guide H, located below and about centrally of the types when in their lowest position. A shaft 35 or rod I passes up through the guide and carries a type cleaner or brush. A cross-piece I' near the bottom of rod I passes through a slot K' in lever K. The lever K is fulcrumed on a bar, lug, or other suitable support L, 40 near one side of the machine, and an arm M of the lever extends upward and terminates in a handle O. A brush S is supported on the upper end of the rod I, so as to lie in a plane below the lowest position of the type 45 or characters on the type-bars when the brush is depressed; but by reciprocating rod I the brush S will be carried up and down past the face of the letters E' on the type-bars. The rod I is thus made the support of the brush 50 and may be a part of the brush. The recip-

location of rod I is effected by means of the bell-crank lever K M, the connection between the end of the lever and the brush-holding rod permitting such reciprocation.

In the machine illustrated, in which the 55 type when depressed occupy an elliptical space, the outside of the brush will be nearly an ellipse, so that when raised the brush will bear on all the letters at one time. If the type are differently arranged, the brush will 60 generally conform to that arrangement.

It will be evident at once to the skilled 65 mechanic that other arrangements of mechanism for lifting and depressing the brush may be devised, which mechanism will be the equivalent to that illustrated. Thus it will appear that the form of lever is not very material, as a straight lever can be readily substituted for a bell-crank lever. Neither is the location important, as the brush-operating mechanism may be at one side or at the back of the machine. The slot-and-pin connection can be reversed in location, or any equivalent connection which will reciprocate the brush may be substituted, and on occasion the lever may be dispensed with and the brush actuated by hand. 70

In my patent, No. 411,421, of September 24, 1889, I describe a rotating-brush having a similar relation to the type of a type-writing 80 machine as the brush herein shown; but the mechanism for moving that brush therein is different, and the movement of the brush was mainly rotary.

What I claim is— 85

1. The combination, with the frame and printing characters of a type-writing machine, of a cleaner-guide in proximity to said printing characters, a type-cleaner, and a support for said cleaner having sliding bearings in 90 said guide.

2. In combination with the printing characters of a type-writing machine, a brush in proximity to said characters, a guide supporting said brush, and a lever connected to 95 and operating said brush to reciprocate it across the face of the printing characters.

3. The combination, with the frame and printing characters of a type-writing machine, of a brush-guide in proximity to said print- 100

ing characters, a brush conforming generally in outline to the position of the printing characters when in their depressed position, and a support for said brush having sliding bearing in the guide, whereby the brush may have a sliding reciprocation past the face of all the printing characters, substantially as described.

4. The combination, with a type-writing machine in which the printing characters are supported on pendent levers, of a bracket or guide below the lowest position of said levers, a sliding guide rod or brush passing through said guide, a brush on said holder, and a lever pivoted in the frame and engaging said brush-

holder to reciprocate the brush, substantially as described.

5. The combination, with a type-writing machine, of a brush-guide, a brush-holder sliding in said guide, a brush carried by said holder, a lever operating on said brush-holder to reciprocate the same, and a handle connected to said lever, all in combination, substantially as described.

In testimony whereof I affix my signature in presence of two witnesses.

ALEXANDER T. BROWN.
